[57] CLAIM

The ornamental design for a screwdriver with swiveled finger hook, as shown and described.

DESCRIPTION

FIG. 1 is a perspective view of the screwdriver with swiveled finger hook showing my new design;

FIG. 2 is a side elevational view thereof, the opposite side elevational view being a mirror image thereof;

FIG. 3 is a top plan view thereof;

FIG. 4 is a fragmentary front elevational view thereof;

FIG. 5 is a fragmentary rear elevational view thereof;

FIG. 6 is a broken-away view of a modified form of the invention.

The portion of the tool not shown in FIGS. 4 and 5 has been omitted for ease of illustration only.

Fig. 2
